UNITED STATES PATENT OFFICE.

OSCAR PETERS, OF CHEMNITZ, GERMANY.

SIPHON FOR DECANTING LIQUIDS.

Application filed October 15, 1927, Serial No. 226,460, and in Germany October 22, 1926.

The invention relates to siphon decanters and has for its object to provide an improved device of this character.

The object of the invention is to provide an automatic siphon decanter for all liquids, especially corrosive liquids, of the type in which an air-tight float valve is arranged between the suction device, which may be the mouth, a suction ball, vacuum pump and the like, and the siphon tube to be evacuated. According to the invention the suction device with float valve is mounted right at the head of the siphon tube without inserting a three-way cock. By this means the result is obtained with certainty that the float valve does not automatically seal the restricted passage of the float chamber until the siphon tubes are fully evacuated, i. e. filled with liquid.

If the evacuation of the siphon were effected from the outlet end or shortly in front of same instead of right at the head of the siphon, the siphon would only be capable of functioning with a tube of small cross-section. It is absolutely impossible for a liquid column, according to the consistency of the liquid, with a diameter of more than about 10 millimeters, normally to run down as a closed column. On the contrary it runs down, according to the law of cohesion, on the inner walls of the outlet pipe without expelling the air downward from the outlet pipe. It penetrates therefore prematurely into the suction device, lifts the float and thereby automatically makes further suction impossible. If now such a siphon is opened in the outlet pipe it cannot function because too much air is enclosed in the siphon. There is no means of removing such air from a siphon.

Based upon the principle that the air, which is contained in the siphon tube and is to be removed, always collects in the upper part of the siphon only, it is necessary to mount the suction device right at the head of the siphon. Since the air is withdrawn from the upper part only of the siphon, the liquid can only enter into the suction device, lift the float and automatically stop the suction, when the siphon tube has been completely evacuated and filled up with liquid. The arrangement of the suction device right at the head of the siphon has the further advantage of direct connection of this suction device to the siphon pipe, dispensing with the use of a three-way cock, which is always very complicated in practise.

In the drawing the new siphoning device is shown in two alternative forms of construction for hand-ball and vacuum pump operation.

Fig. 1 shows in section the construction with hand-ball operation for small siphons and

Fig. 2 showing in section a vacuum pump construction for large siphons.

The siphon comprises the pipe 1 which dips below the liquid in the vessel to be emptied or decanted, the head or bend 1¹ and the outlet pipe 1³ which continues to a point below the liquid level outside pipe 1 and is closed at the bottom by a cock. In the head 1¹ of the siphon is a projection with opening 1² which is internally screw-threaded to receive the screwed end of a sleeve 2. 5 is a float chamber with an opening at the bottom where it is cemented to sleeve 2 by means of cement capable of resisting acid and/or alkali. Within the float chamber 5 is the float 7 which is provided at the top with a plug or valve member 7¹ adapted to seat in the opening 5¹ at the top of the float chamber which leads to the safety chamber or splash catching chamber 8. 9 is a connection to the rubber ball 10 provided with valves 11 and 12. 3 is a protective casting screwed on the sleeve 2 at the bottom and the cover 4 at the top.

When the india-rubber ball 10 is pressed the air enclosed in it flows out through the valve 12, the valve 11 being then closed against downward flow. When the ball is released, a reduction in pressure takes place in it whereby the valve 11 is opened and the valve 12 closes. Air is now sucked through the valve 11, the connecting tube 9, the safety chamber 8 and the float chamber 5 from the siphon tube 1. The operation of the ball is repeated a few times until the liquid rises in the inlet branch 1 of the siphon, flows round the bend or head 1¹, passes the projection 1² and fills the outlet branch 1³ which is closed at the bottom with a cock. As soon as the whole siphon tube is filled, the liquid enters the float chamber 5 and raises the float 7 the ground head 7¹ of which seats in the constriction 5¹ and thus effects an air-tight seal. This indicates that the siphon is filled with liquid and the decanting operation can be commenced. Of course, it is possible in place of the valve 11 to provide a valve at the entrance to the float chamber at the bottom or to grind the float 7 at the bottom into its chamber so that it constitutes a valve itself.

The safety chamber 8 is provided in order to catch any drops of liquid projected upwards through too strong suction so that the penetration of even the smallest quantity of liquid into the actual suction device is made impossible.

The jacket 3 provided for protection of the float valve may, when the float is made of glass, be provided with openings to permit 10 the operation taking place in the float chamber to be seen.

Referring to Fig. 2 the rubber ball 10 is replaced in this case by means of a small 15 vacuum pump having a piston 15 adapted to be reciprocated in a cylinder connected at one end through a flexible pipe 13 to the siphon valve, a valve 11 mounted on a flap 14, being provided between the cylinder and the siphon valve, and the other end of the cylinder being 20 provided with apertures 17 leading to the atmosphere. The cylinder is pivoted at one end to a fixed bracket and the piston rod 16 is connected to a crank arm 18 adapted to be rotated by means of an arm or handle 19. 25 On turning the handle 19, the piston is reciprocated in the cylinder and, at each outward stroke the valve 11 opens and valve 12 closes; at each inward stroke the valve 11 closes and the valve 12 opens. Thus the air 30 is gradually evacuated from the siphon pipes. The crank arm 19 can be operated by hand or by mechanical means.

Finally it may be observed that with the present invention it is possible also to employ 35 any continuous means of vacuum reduction. It does not matter how large the diameter of the tube is or whether the liquid in the vessel to be emptied stands at an extraordinary low level. In other words, it does not 40 matter how much space filled with air has to be evacuated in the siphon tube. The evacuating device arranged at the head of the siphon can be continuously operated, no matter whether a small suction ball or a small 45 suction pump is employed, until the tubes are completely evacuated and filled with liquid.

I claim:—

1. A siphon for decanting liquids comprising the combination of a siphon pipe with 50 upflow and downflow branches, a branch passage at the head of said siphon pipe, a float chamber into which said branch passage opens, a constricted passage at the top of said float chamber, a splash catching chamber 55 having a protected outlet and into which

said constricted passage opens, a suction pump connected to said constricted passage and a float in said chamber having its upper part plug-shaped and adapted to seat in said constricted passage.

60

2. A siphon for decanting liquids comprising the combination of a siphon pipe with upflow and downflow branches, a short tubular projection at the head of said siphon between said upflow and downflow branches, a sleeve fitted to said tubular projection, a float chamber cemented to said sleeve and communicating at the bottom with said siphon head and at the top with a splash-catching chamber, a float in said chamber having a plug valve member at the top adapted to seat in the passage communicating with the splash-catching chamber, a suction pump connected to said splash catching chamber, a piston in said suction pump and means for 70 operating said suction pump.

75

3. A siphon for decanting liquids comprising the combination of a siphon pipe with upflow and downflow branches, a branch passage at the head of said siphon pipe, float 80 chamber into which said branch passage opens, a constricted passage at the top of said float chamber, a splash-catching chamber having a protected outlet and into which said constricted passage opens, a suction mechanism connected to said constricted passage, two valves in the suction element, one between said suction element and the float casing, and the other controlling a connection to the outside air, and a float in said chamber having 85 its upper part plug shaped and adapted to seat in said constricted passage.

85

4. A siphon for decanting liquids comprising the combination of a siphon pipe with upflow and downflow branches, a short tubular projection at the head of said siphon between said upflow and downflow branches, a sleeve fitted to said tubular projection, a float chamber cemented to said sleeve and communicating at the bottom with said siphon head and at the top within a splash-catching chamber, a suction mechanism connected to said splash-catching chamber, two valves, secured inside of this suction element, one controlling the connection with the float 95 chamber and the other opening to the atmosphere.

100

In testimony whereof I have affixed my signature.

OSCAR PETERS.
